UNITED STATES PATENT OFFICE

165,312

TABLE LAMP

Kurt Versen, Tenafly, N. J.

Application December 11, 1950, Serial No. 13,361

Term of patent 14 years

(Cl. D48—20)

To all whom it may concern:

Be it known that I, Kurt Versen, a citizen of the United States, residing at Tenafly, in the county of Bergen and State of New Jersey, have invented a new, original, and ornamental Design for a Table Lamp, of which the following is a specification, reference being had to the accompanying drawings, forming part thereof.

In the drawings:

Fig. 1 is a perspective view of a table lamp showing my new design;

Fig. 2 is a side elevational view; and

Fig. 3 is a top plan view.

I claim:

The ornamental design for a table lamp, as shown.
